[57] CLAIM

The ornamental design for a smoke detector cover with light, as shown and described.

DESCRIPTION

FIG. 1 is a top perspective view of a smoke detector cover with lights showing my new design;

FIG. 2 is a top plan view thereof;

FIG. 3 is a side elevational view thereof, the opposite side elevational view being a mirror image of that shown;

FIG. 4 is a bottom plan view thereof.

FIG. 1.

FIG. 2.

FIG. 3.

FIG. 4.
